Primary Examiner—Lucy Lieberman(74) *Attorney, Agent, or Firm*—McGlew and Tuttle, P.C.(57) **CLAIM**

The ornamental design for a watch, as shown and described.

DESCRIPTION

FIG. 1 is a top view of my new watch;

FIG. 2 is bottom view thereof;

FIG. 3 is right side view thereof;

FIG. 4 is a left side view thereof;

FIG. 5 is a front end view thereof;

FIG. 6 is rear end view thereof; and,

FIG. 7 is a perspective view thereof.

The broken lines in FIGS. 2 and 4 are used to show portions of the watch that do not form part of the claimed design.

1 Claim, 5 Drawing Sheets Fig. 1

Fig. 2

FIG. 3

FIG. 4

FIG. 7
